UNITED STATES PATENT OFFICE.

SAMUEL P. EDMONDS, OF BROOKLYN, NEW YORK.

LIFE-PRESERVER.

1,295,715.

Specification of Letters Patent. Patented Feb. 25, 1919.

Application filed January 17, 1919. Serial No. 271,632.

To all whom it may concern:

Be it known that I, SAMUEL P. EDMONDS, a citizen of the United States, residing at Brooklyn, in the county of Kings and State of New York, have invented certain new and useful Improvements in Life-Preservers, of which the following is a specification.

This invention relates to life preservers of the type which is composed of a plurality of blocks of buoyant material such as wood or cork flexibly united into a girdle and which may be quickly adjusted about the waist.

This type of life preserver comprising a series of blocks without an external covering is exceedingly simple and cheap to manufacture which is an important consideration for steamboat companies requiring thousands for the equipment of each vessel. While life preservers constructed in this manner are efficient as far as their buoyant qualities are concerned, they are more or less liable to injure the wearer when tossed about by the waves and in a rough sea are positively dangerous as the blocks are thrown about since a blow upon the head or face by one of these blocks is very liable to not only stun the person but cause greater injury. One of the objects of my invention is to provide a life preserver of this uncovered block type combined with a collar member which will thoroughly protect the face and head of the wearer, thereby overcoming the objections and dangerous features which have heretofore attended the use of any and all of this type.

In the accompanying drawings, Figure 1 is a perspective view showing a life preserver embodying my invention and its normal position when in position on the wearer; Fig. 2 is a perspective view showing the manner in which the collar portion receives the blows of the blocks when tossed about by the waves so as to completely protect the head and face of the wearer; Fig. 3 is a perspective view of the life preserver with the parts separated to show the construction; and Figs. 4, 5 and 6 are enlarged detail views of certain parts, Fig. 5 being taken on the line 5-5 and Fig. 6 on the line 6-6 of Fig. 3. The main portion of the life preserver consists of a series of blocks 2 such as cork or suitable light buoyant wood such as balsa wood, which are united into a girdle by means of cords or

ropes 3 passing through holes bored adjacent the ends, the holes through the end blocks being bored diagonally in the manner illustrated in Fig. 4, to bring the free ends of the ropes 3 near the outer sides of the blocks to facilitate tying. The blocks are preferably rectangular with the edges rounded or beveled, those upon either side of the arms being cut away upon adjacent upper corners as indicated at 2^a to permit the wearer to have free unimpeded movement of his arms.

The collar part 10 is constructed with an outer cover or envelop filled with kapok 12 or other suitable buoyant material. It is of sufficient length to permit the ends to meet or lap and is provided with straps or tapes 11 by which it may be secured in position as illustrated in Figs. 1 and 2. The forward portions of the collar upon either side are connected by straps 14 with the upper girdle cords 3 at the front, and serve to unite the parts and to position the collar. The straps 14 are either continued or else separate straps 15 are employed to form suspenders 15, crossing at the back and connected to the upper cord 3 upon either side of the middle block, serving to support the girdle at the back and also to maintain the collar in position. I may fill the upper triangular space between the collar and the suspender straps with a fabric 16, which serves not only as a reinforcement but prevents the straps from entanglement and also to prevent the wearer from inadvertently inserting his arm in through this part in the confusion and excitement of a disaster.

In some cases I may dispense with the rear straps 15 and the reinforcement 16, securing the collar part to the girdle cords only by the straps 14. Instead of employing an equal number of blocks upon either side, I may arrange more on one side than on the other and in this manner bring the ends of the cords or ropes 3 at one side.

Naval engineers and seamen who have had experience with the present types of life preservers and those of the uncovered girdle type having a series of blocks strung together by means of ropes, will appreciate the advantages of the present invention which enables this type to be used without subjecting the wearer to the constant menace of receiving a blow upon the face or head from the blocks whenever he is tossed about by the waves. The buoyant collar supports the

head and coöperates with the girdle members to maintain the body in the proper position to maintain the face uppermost, but it also performs the very important function

5 of receiving the blows and absorbing the shocks of the blocks as they are thrown upward toward the head by the impact of the waves.

I have described in detail the construction
10 illustrated in the accompanying drawings for the purpose of disclosing one embodiment of my invention but it will be evident that various changes may be made therein without departing from the invention. The

15 buoyant blocks may take other forms and may be secured together into a girdle by means of webbing of fabric of any suitable character.

I claim:—

20 1. A life preserver having a main girdle portion comprising a plurality of buoyant blocks united loosely by means of a plurality of connecting cords or ropes thereby permitting independent movement of the blocks,
25 and a soft buoyant collar part provided

with means to secure it around the base of the head in position to receive impacts from the blocks as they are thrown upward by the waves.

2. A life preserver having a main girdle 30 portion comprising a plurality of buoyant blocks united loosely by means of a plurality of connecting cords or ropes thereby permitting independent movement of the blocks, and a yieldable collar part provided with 35 means to secure it about the base of the head with the forward ends brought together, and connecting means extending between the collar part and the girdle portion.

3. A life preserver comprising a body portion 40 consisting of a plurality of buoyant blocks bound together to form a girdle member, and a soft buoyant collar provided with means to secure it about the base of the head, and connecting means securing the collar to the girdle member at the back and at the front thereof.

In testimony whereof I affix my signature.

SAMUEL P. EDMONDS.
